UNITED STATES PATENT OFFICE

120,691

DESIGN FOR A WINDOW SHADE OR SIMILAR ARTICLE

Chester H. Norton, Bronxville, N. Y.

Application February 2, 1939, Serial No. 82,727

Term of patent 14 years

To all whom it may concern:

Be it known that I, Chester H. Norton, a citizen of the United States, residing at Bronxville, county of Westchester, State of New York, have invented a new, original, and ornamental Design for a Window Shade or Similar Article, of which the following is a specification, reference being had to the accompanying drawing, forming a part thereof.

Fig. 1 is a front elevational view of a shade showing my new design; and

Fig. 2 is a side view of the shade of Fig. 1.

The back of the shade conforms with the disclosure of Fig. 1.

I claim:

The ornamental design for a window shade or similar article, substantially as shown and described.

CHESTER H. NORTON.
